UNITED STATES PATENT OFFICE.

RALPH HINCHLIFF, OF ROCKFORD, ILLINOIS, ASSIGNOR TO BURSON KNITTING COMPANY, OF ROCKFORD, ILLINOIS, A CORPORATION OF ILLINOIS.

OPENWORK KNITTED FABRIC AND METHOD OF PRODUCING SAME.

Application filed September 1, 1922. Serial No. 585,725.

To all whom it may concern:

Be it known that I, RALPH HINCHLIFF, a citizen of the United States, residing at Rockford, in the county of Winnebago and State of Illinois, have invented certain new and useful Improvements in Openwork Knitted Fabrics and Methods of Producing Same, of which the following is a specification.

10 This invention pertains in general to knitted fabrics and relates more particularly to knitted fabrics of the open-work type and to the method of producing the same.

While a fabric made in accordance with 15 my invention is capable of a wide variety of uses, I have illustrated the same herein as embodied in a stocking of the seamless fashioned type.

Open work stockings and other fabrics 20 have been commercially made prior to my invention by the drop stitch method, i. e., at spaced intervals across the fabric one or more stitches are dropped, or, in other words, floated instead of being knit into a stitch 25 formation. The floating yarns connecting adjacent knitted wales provide the open work appearance. These floating yarns, however, all extend straight across from wale to wale and are disposed substantially 30 in parallelism and under the same tension.

My present invention aims to provide an open work fabric of a novel structure and appearance, in which the open work is formed by ravelling one or more knitted 35 wales of the previously knit fabric, the ravelled yarns of which, as the result of having been previously knit and thereby kinked or curled, assume different positions and impart to the fabric a different appearance than 40 open work formed by the drop stitch method.

My invention contemplates also giving to the fabric a further distinctive and novel appearance by incorporating in the wales 45 which are to be subsequently unravelled, draw or tuck stitches, the elongated loops of which, when unravelled, are longer than the floating yarns extending between the wales adjoining the run. The open work, therefore, comprises the unravelled yarns of the tuck stitches and the shorter floating yarns and consequently when the fabric is laterally stretched, as it is in a stocking when on a 50 leg, the floating yarns being shorter are 55 under a greater tension than the unravelled

draw stitch yarns. This difference in tension causes those stitches of the adjacent wales with which the floating yarns are connected to be drawn very tightly and somewhat distorted by the tension of the floating 60 yarns, while the stitches with which the unravelled draw stitch yarns are connected are not subjected to as great a tension and therefore retain their original shape and the draw stitch yarns remain loose and 65 kinked or distorted, lending a novel and distinctive appearance to the fabric.

Another feature of my invention which adds to the attractiveness of the fabric, is the incorporation in the knitted webs between 70 the open work stripes of draw stitches, tuck stitches, or other ornamental stitches under increased tension, which when such tension is partially relieved by the ravelling of a neighboring wale stand out in relief to impart to the fabric a neat and pleasing appearance.

For the purpose of facilitating an understanding of my invention, I have illustrated on the accompanying drawing a preferred 80 embodiment thereof from an inspection of which when considered in connection with the following description, the fabric, its method of production, and many of the advantageous features thereof should be readily understood and appreciated. 85

Referring to the drawings:

Fig. 1 is a side elevation of a stocking made in accordance with my invention;

Fig. 2 is a fragmentary enlarged view 90 showing the structure of the fabric prior to the ravelling operation;

Fig. 3 is a similar view, showing the open work resulting from the ravelling; and

Fig. 4 is an edge view of the fabric shown 95 in Fig. 3.

The particular fabric illustrated comprises a series of knitted webs, those illustrated in Fig. 2 being designated by reference characters 5, 6, 7 and 8, these webs being 100 united in the fabric when knit by wales 9, 11 and 12, which are subsequently unravelled or run. The entire fabric may consist entirely of plain stitches, but preferably each web includes a series of draw or tuck 105 stitches 13 which lend attractiveness to the fabric, and obviously each web may comprise a greater or less number of wales than three which are shown on the drawings for illustrative purposes merely. 110

The intervening wales 9, 11, 12, etc., also preferably comprise draw stitches 14, and may also include plain stitches 15, as shown. In the production of the draw stitches 14, the yarns 16 are floated at the back of the fabric in the usual manner.

When the production of the fabric nears completion, or at any desired point therein, the yarn is dropped off from the needles 10 which form the intervening wales 9, 11, 12, etc. In forming a stocking of the seamless full-fashioned type, which is knit from the toe upwardly, the yarn is dropped off just before the formation of the stocking top or 15 approximately at a point indicated by dotted line 17 in Fig. 1. The fabric is then stretched, which causes the wales in which the yarn has been dropped to run or ravel, with the result that the webs then become separated 20 by intervening open work stripes designated in Fig. 3 by reference characters 18 and 19. This running or ravelling will continue throughout the length of the wales, unless it be in some way stopped, and in Fig. 1 I 25 have illustrated lines of stitching 21 and 22 adjacent the heel and toe of the stocking which hold the yarn and limit the extent of the run but, obviously such unravelling may be stopped at any desired location.

30 When the intermediate wales 9, 11, 12, etc. are run or ravelled, the floating yarns 16 are stretched taut between the marginal wales of adjacent webs, and if considerable tension is exerted laterally of the fabric, the 35 stitches to which these yarns are connected at each end become tightened and somewhat distorted. The yarns forming plain stitches 15 are drawn substantially taut, as indicated by 15' in Fig. 3, although the kink or distortion of the yarn resulting from its having 40 been knit, causes these yarns 15' to assume irregular positions except when the fabric is under considerable tension. The yarns forming the draw stitches 14, being considerably longer than either the yarns 15 or 15', are drawn into irregularly disposed loops or 45 curves, indicated by reference character 14' in Figs. 3 and 4.

The particular fabric disclosed, includes in 50 its open work structure, three groups of yarns, namely, the floating yarns 16, which lie substantially straight, the plain stitch yarns 15', which are more or less kinked depending upon the tension exerted upon the 55 yarns, and the draw stitch yarns 14' which are looped or kinked to a considerable degree, since no appreciable tension is exerted upon these yarns even when the fabric is subjected to considerable tension. Each 60 openwork stripe therefore consists of successively arranged groups of yarns, each group of which includes yarns of three different lengths and tensions extending between adjacent webs. The appearance of a 65 fabric of this character may obviously be

varied by increasing or diminishing the relative proportions of plain and draw stitches in the wales which are intended to be run or ravelled after the knitting operation is completed.

70 It will be understood, therefore, that I have provided a fabric of the open work type which differs both in its structure and in its method of production from open work fabrics as customarily produced and that the 75 fabric, as the result of the different lengths of the yarns in the open work stripes, presents a novel and striking appearance which is capable of variation by varying the 80 stitches either in the fabric webs, or in the open work wales, or in both, as desired.

I claim:

1. An open work knitted fabric, comprising alternately disposed webs and open work stripes, each web consisting of a plurality of 85 knitted wales, and each stripe consisting of transversely extending yarns arranged in successive groups throughout the length of the stripe, each group comprising yarns of varying lengths.

90 2. An open work knitted fabric, comprising alternately arranged knitted webs and open work stripes, the stripes consisting of transversely disposed yarns under different tensions connecting said webs and arranged 95 in successive similar groups throughout the length of each stripe.

3. An open work knitted fabric, comprising a knitted web including plain and draw stitches, and an open work stripe including 100 yarns from ravelled draw stitches.

4. An open work knitted fabric, comprising a knitted web including plain and draw stitches, and an open work stripe including the ravelled yarns of plain and 105 draw stitches.

5. An open work knitted fabric, comprising a knitted web, and open work stripes including floating yarns and the ravelled 110 yarns of plain and draw stitches.

6. A stocking, consisting of alternately disposed knitted webs and open work stripes, the stripes including straight yarns and kinked yarns.

115 7. A knitted stocking, consisting of alternately arranged knitted webs and open work stripes, the webs comprising plain stitches and draw stitches, and the stripes comprising straight floating yarns and longer kinked ravelled yarns.

120 8. A seamless fashioned stocking, comprising alternately arranged knitted webs, including plain stitch wales and tuck stitch wales, and open work stripes including straight floating yarns, ravelled plain stitch 125 yarns and ravelled tuck stitch yarns of greater length than the floating yarns.

9. An open work knitted fabric comprising spaced webs including plain and tuck stitches, and intervening open work 130

stripes including ravelled plain stitch yarns and ravelled tuck stitch yarns.

10. An open work knitted fabric comprising spaced knitted webs each including a plurality of wales, and intervening open work stripes each including ravelled yarns from knitted plain and tuck stitches.

11. An open work knitted fabric comprising spaced webs each consisting of one or more wales including tuck stitches, flanked by plain stitch wales, and open work stripes comprising ravelled yarns.

12. An open work knitted fabric comprising spaced webs each consisting of one or more wales including tuck stitches, flanked by plain stitch wales, and open work stripes comprising ravelled plain and tuck stitch yarns.

13. The method of producing an open

work knitted fabric which consists in knitting a solid fabric to include both plain and tuck stitches in predetermined wales thereof, and ravelling certain of the wales only, including tuck stitches, to thereby produce open work stripes comprising yarns of ravelled plain and tuck stitches, alternating with knitted webs in which the remaining tuck stitch wales are incorporated.

14. The method of producing an open work knitted fabric which consists in knitting a solid fabric to include both plain and tuck stitches in predetermined wales thereof, and ravelling tuck stitch wales to thereby produce open work stripes comprising yarns of both ravelled plain and tuck stitches, alternating with solid knitted webs.

RALPH HINCHLIFF.
